UNITED STATES PATENT OFFICE.

JEREMIAH VANDERBILT, OF BROOKLYN, NEW YORK, ASSIGNOR TO ROBERT LEFFERTS, OF SAME PLACE.

DESIGN FOR A CANDLE-SHADE.

SPECIFICATION forming part of Design No. 26,788, dated March 23, 1897.

Application filed February 4, 1897. Serial No. 622,052. Term of patent 7 years.

To all whom it may concern:

Be it known that I, JEREMIAH VANDERBILT, a citizen of the United States, residing at Brooklyn, county of Kings, and State of New York, have invented and produced a new and original Design for Candle-Shades and the Like, (Case C,) of which the following is a specification.

My invention relates to a design for a candle or lamp shade; and it consists in the configuration and disposition of parts substantially as illustrated in the accompanying drawings, forming part of this specification, in which—

Figure 1 is a plan view; Fig. 2, a side elevation, and Fig. 3 a sectional elevation.

The design consists of a plurality of ranges or rings of bell-like flowers disposed concentrically upon the bell-like base, substantially as hereinafter described.

The bell-like base 1 of the shade, which has crinkled surfaces inside and outside, is provided with a thick and annular base piece or ring 2. At the top of the base 1 is a conical ring 3, surmounted by an annular ring 4.

The foregoing serves as a support and outline giving body for the disposition of the concentric rings or ranges of flowers.

The exterior ornamentation of the base 1 consists in the three concentric ranges or rings 5 6 7, the upper flowers being secured adjacent the ring 4, the lower ring secured to the base above the base piece or ring 2, and the central ring interposed between the upper and lower ranges. The centers of the flowers of each range, as indicated by the pistils, lie substantially in the same concentric line, whereas the pistils of each range of flowers are staggered one in relation to the other, so as almost to completely cover or envelop the outer surface of the base. The petals of the upper range of flowers extend above the ring 4. The flowers are bell-like and extend boldly out from the base.

Having described my invention, I claim—

The design for a candle-shade or the like, substantially as herein shown and described.

Signed at the city, county, and State of New York this 30th day of January, 1897.

JEREMIAH VANDERBILT.
